US0D1105074S

(12) **United States Design Patent** (10) **Patent No.:** **US D1,105,074 S**
(45) **Date of Patent:** **** Dec. 9, 2025**

(54) **GRAPHICS TABLET**

(71) Applicant: **Hanvon Ugee Technology Co., Ltd.**,
Guangdong (CN)

(72) Inventor: **Xinhang Zou**, Guangdong (CN)

(73) Assignee: **Hanvon Ugee Technology Co., Ltd.**,
Guangdong (CN)

(**) Term: **15 Years**

(21) Appl. No.: **29/911,956**

(22) Filed: **Sep. 12, 2023**

(30) **Foreign Application Priority Data**

Mar. 13, 2023 (CN) 202330111806.8

(51) **LOC (15) Cl.** **14-02**

(52) **U.S. Cl.**

USPC **D14/389**; D14/341

(57) **CLAIM**

The ornamental design for a graphics tablet, as shown and described.

DESCRIPTION

FIG. 1 is a front, left-side perspective view of a graphics tablet showing my new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines shown in the drawings depict portions of the graphics tablet that form no part of the claimed design.

1 Claim, 8 Drawing Sheets
